SHOE TREEING AND SHAPING MACHINE

Harry E. Dow and Irving B. Andrews, Beverly, Mass., assignors to United Shoe Machinery Corporation, Borough of Flemington, N. J., a corporation of New Jersey

Application October 26, 1938, Serial No. 237,128

21 Claims. (Cl. 12—51)

This invention relates to machines for making shoes and more particularly to a machine for treeing and shaping shoes. After the lasting operations have been completed and the last is removed from a shoe, the shoe is ready for the treeing and shaping operations which impart to it the desired final finished appearance before it is packed for shipment. Heretofore, those operations have been carried out separately and on different machines. Usually the shoe is first mounted on a tree leg of a treeing machine, which is generally of the turret type, and the treeing operations are carried out upon the treed shoe; the treeing operations including the step of cleaning which in most cases consists of washing the shoe and in practically all cases results in dampening the upper leather. Upon the completion of this phase of the treeing operation, the practice is to leave the shoe on the tree leg to dry while similar operations are being carried out on another treed shoe, after which the first shoe is brushed and removed from the machine, and, in the case of some shoes such as pumps, for example, the width of the foot receiving shoe opening is reduced in the pressing operation so that the top of the shoe will hug the foot of the wearer, and in the same operation the opening is given a somewhat symmetrical appearance that is pleasing to the eye. It is an object of this invention to provide a machine wherein both the treeing and the shaping operations may be carried out without removing a shoe from the machine and thereby save the time which has heretofore been used in changing a shoe from one machine to the other. To this end, the invention provides a machine comprising a shoe tree which is mounted for movement between a treeing position and a shaping position, and shoe pressing means arranged for shaping engagement with a shoe on the shoe tree when the tree is in the shaping position. This construction makes it possible both to tree and to shape a shoe without removing it from the shoe tree, and in addition also provides an arrangement whereby a shoe which has been dampened in the treeing operation may simultaneously be dried and shaped as the shoe will be drying while it is being pressed by the pressing means.

As a further feature of this invention means are provided in the machine for utilizing an operator's time when the shoe tree is in the shaping position. As illustrated, this means comprises another shoe tree which is also mounted for movement between the treeing position and a

shaping position, the disposition of the shoe trees being such that when one shoe tree is in a shaping position the other will be in the treeing position thus making it possible for an operator to carry out treeing operations on a shoe on one shoe tree while a shoe on the other shoe tree is being dried and shaped.

In accordance with another feature of this invention, there is illustrated an improved mechanism for pressing and shaping shoe uppers. In the illustrated embodiment of this feature of the invention, the mechanism comprises shoe pressing means and a tree leg mounted for movement into and out of a shaping position where it may be engaged by the pressing means, the tree leg comprising an expandible shoe form shaped to give a shoe a restricted opening of pleasing appearance, and provided with heating means arranged to apply heat to a shoe upper adjacent to the top opening thereof to facilitate the shaping and drying of a shoe on the form.

Invention is also to be recognized in the novel construction of the extensible shoe form whereby the sides of a shoe on the shoe form are heated and supported throughout their length regardless of the adjustment of the shoe form, and also in the shape of the heel section of the shoe form which adapts it for removal from a shoe without distorting the shape of the shoe opening.

With the above and other objects in view, the invention will now be described in reference to the accompanying drawings and will be pointed out in the appended claims.

In the drawings:

Fig. 1 is a plan view looking down on the machine and showing one of the shoe trees in the treeing position and the other located between one section of the shoe shaping pads;

Fig. 2 is a side elevation of the machine, partly in section, taken along the line II—II of Fig. 1;

Fig. 3 is a view on a reduced scale of one of the expandible shoe forms used in the illustrated machine, and is broken away and in section to illustrate the expanding means;

Fig. 4 is a view taken along the line IV—IV of Fig. 3 showing a cross-section of the forepart of the shoe form and also illustrating the connections between the forepart and the remainder of the form;

Fig. 5 is a plan view, taken along the line V—V of Fig. 1, of a portion of the right tree leg and showing the upper of a shoe on the shoe form being pressed between the presser members;

Fig. 6 is a view taken along the line VI—VI of Fig. 1 showing a portion of the actuating

mechanism for the shoe pressing means, and

Fig. 7 is a sectional view taken along line VII-VIII of Fig. 5.

The illustrated machine is of the type shown in 5 Letters Patent of the United States No. 442,034, granted December 2, 1890, upon application of A. B. Fowler, to which Letters Patent reference may be had for a description of parts of the machine not herein fully shown or described.

10 The illustrated machine comprises a bench 12 (Fig. 2) having an extensible standard 14 which carries a forwardly extending bearing plate 16 that has a semi-circular upright flange 18. The flange 18 has a central opening in which is slidably mounted a plunger 20 that controls the expansion of the shoe forms as will be explained fully hereinafter, the plunger 20 being moved inwardly to expand the shoe forms by a lever 22 which is actuated by a foot lever 24 through a 15 connecting link 26. The bearing plate 16 is provided with a pivot stud 28 upon which is rotatably mounted a turret 30 (Figs. 1 and 2) having two hollow arms 32, 34 in which are journaled tree legs 36, 38. The swinging movement 20 of the turret 30 is limited by a pair of stops 40, 42 on the support plate 16 which are so located in the path of movement of a lug 44 on the turret 30 that when the lug is in engagement with one of the stops, one or the other of the 25 tree legs will be positioned centrally of the machine where the treeing operations may conveniently be carried out by the operator. Each of the tree legs includes an expandible shoe form which is controlled by a reciprocating rod 35 46 (Fig. 1) having a collar 48 on its inner end which is slidably mounted in the inner end of the hollow turret arm. The reciprocating rod 46 is connected to the plunger 20 by a cup shaped sleeve 50 which is slidably mounted on the rod 46 (Fig. 1) and a spring 54 interposed between the sleeve 50 and the collar 48, the sleeve 50 having a depending arm 51 (Fig. 2) in which is mounted a roller 52 that is engaged by the plunger 20 when the tree leg is in the central 40 50 treeing position. Thus, inward movement of the plunger 20 is transmitted to the rod 46 by the sleeve 50 and the spring 54. The rod 46 is urged outwardly by a spring 59 which is sleeved on the rod between a plug 60 threaded in the inner 55 end of the tree leg and a collar 62 fast to the rod. The forward ends of the hollow arms 32 and 34 are provided with longitudinal slits 53 (Fig. 2) and the shoe trees are clamped in different rotative positions by clamping wheels 54 or 55 mounted on the respective arms. The trees are held against longitudinal movement in the hollow arms by studs 56 or 57 (Figs. 1 and 2) which are seated in peripheral grooves 58 formed on the inner ends of the treeing legs. The structure so far described is similar to that disclosed 60 in the above-mentioned patent to Fowler.

As the shoe trees are similar to one another only one of them will be described in detail and like parts in both shoe trees will be given the 65 same reference characters. The shoe tree consists of an upper leg portion 66 (Fig. 1) and a lower leg portion 70, the inner end of the upper leg portion being attached to the hollow turret sleeve 32 by pins 67 and the other end of the 70 upper leg portion being flared outwardly and provided with an electrical terminal box 68 having projecting brushes 80. The lower leg portion 70 is provided with an extension 72 on its inner end which is journaled in the hollow arm 75 32 of the turret 30 and has mounted on its outer

end an expandible shoe form 74 which is provided with an electrical heating unit 76. To supply the heating unit 76 with current in all of the rotative positions of the tree leg, the lower leg portion 70 is provided with an outwardly extending dished housing 77 in which are mounted collector rings 78 disposed in a path of the brushes 80 depending from the terminal box 68 (Fig. 1); the collector rings being connected with the heating unit 76 by a cable 79. 10

To assist in attaining that object of the invention, which relates to reducing the width of the top opening of a shoe and giving it a pleasing appearance, the section of the shoe form 74 contiguous to the shoe opening is given the shape 15 of Fig. 7 which is a curve of short radius at the rear or heel end, a curve of larger radius at the throat and straight sides interconnecting the ends of these curves, the sides being non-parallel and diverging toward the front. The sides also slope inwardly in a heightwise direction (Figs. 4 and 5) in the area adjacent to the 20 top edge of a shoe. 25

The expandible shoe form 74 (Fig. 3) consists of a rear portion 82 which is attached to the tree leg 36 and a forepart 84 that is slidably mounted on the rear portion 82 and is operatively connected with the reciprocating rod 46. The forepart 84 consists of a wooden form (Fig. 3) having a central groove in which is fastened a metal channel strip 86 shaped to slide on the T-head 92 (Fig. 4) of a carrier 100, the metal channel strip extending beyond the rear end of the form 84 and the extending portion having an opening therein for engagement with a latch 90 on the head 92 (Figs. 3 and 4). The carrier 100 is provided with flanges 94 and 96 which are slidably received in grooves formed in the rear portion 82 (Fig. 4) and is moved back and forth in those grooves by the reciprocating rod 46 which is connected to the carrier 100 by a gear train that consists of (Fig. 3) a rack 47 on the rod 46, pinion 102, gear segment 98 and rack 45 101 on the carrier 100. With the above arrangement the tree legs are adapted to cooperate with a range of sizes as foreparts of different sizes may readily be interchanged by releasing the latch 90 and removing one forepart and replacing it with another of a different size. 50

To support the top edge of shoe uppers back of the throat portions, metal plates 104, 106 are provided on the shoe forms which extend from the forepart 84 back about half way to the heel. These plates are slidably mounted on tracks 108, 110 (Fig. 3) in recesses on the sides of the rear portion 82 of the shoe form and are connected with the gear segment 98 for movement with the forepart 84 by a pin 114 which is mounted on the gear segment with its ends seated in recesses 112 (Fig. 4) in the plates 104, 106. Thus, the metal plates 104 and 106 will be moved simultaneously with the forepart 84 by the gear segment 98. Forward movement of the plates 104, 65 106 will uncover the recesses in which they are seated and to cover these recesses thin cover plates 116 (Figs. 1 and 7) are attached to the rear portion 82 and extend between the rear ends of the slides and the rear part of the shoe form. 70 The portion 105 (Fig. 4) of the plates 104, 106 which contacts the shoe upper lining adjacent to the top line and also the side sections of the rear portion 82 of the shoe form are sloped inwardly so that when an upper is pressed against 75

the sides of the shoe form (Figs. 5 and 7) in their downward position so as to hold the pads pressed against the shoe form.

In the illustrated embodiment of this invention, as is best shown in Fig. 5, the pads 128 and 130 are arranged to engage only the top portion of a shoe upper so that the shoe shaping pressure is localized in the area of the upper that it is desired to shape, which is the area adjacent to the top line of the shoe. Another feature of the invention lies in the shape of the rear or heel section 32 of the shoe form which is made narrower than the opening of the shoe upper so that when the top portion of the upper is pressed against the sides of the form the lower portion of the heel section of the upper, which is reinforced by a counter, will be bent gradually inward (Fig. 5). Thus, when the pads are moved away from the upper, the counter will move back to its normal upright position carrying the upper with it thereby widening the heel portion of the shoe opening so that the shoe may readily be removed from the form without disturbing the shape which has just been given to the shoe opening. It is to be understood, however, that the shape and dimension of the heel portions of the shoe forms and also those of the presser pads may be varied so that all or any desired part of the shoe upper can be supported and pressed without departing from the spirit of this invention.

The operation of the machine is as follows: A forepart 84 of an appropriate size is first selected and is slid over the head 92 of the carrier 100 and is fastened thereon by the latch 90, the connections being as shown in Fig. 3. A shoe is then placed upon the tree leg which is in the central or treeing position, that is, in the position occupied by the leg 36 in Fig. 1, and the lever 24 is depressed to expand the shoe form by actuating the control system in the following manner. Downward movement of the lever 24 causes rotation of the lever 22 (Fig. 2) which moves the plunger 20 inwardly carrying the roller 52 and sleeve 50 inwardly with it, thereby compressing the spring 54 (Fig. 1) and through it moving the rod 46 and rack 47 inwardly; movement of the rack 47 in this direction will be transmitted to the carrier 100 and the forepart 84 will be moved forwardly to expand the shoe form a desired amount. The side plates 104, 106 are moved with the forepart by the pin 114 (Fig. 4) which is carried by the gear segment 98 and is seated in recesses 112 in the plates. After the shoe form has been expanded, the shoe tree is rotated about its axis by the operator as desired for the treeing operations and upon the completion of these operations the shoe is moved to a horizontal position with the heel pointing toward the adjacent presser pads. This is necessary because the shoe form 74 is shaped so that the sides diverge outwardly from the heel to the throat portion and the presser pads 128, 130 are arranged to receive the shoe form between them heel first (Fig. 7). The turret 30 is then swung until the projection 44 on the turret engages the stop 40 when the tree leg 36 will be in the treeing position formerly occupied by the tree leg 36 and the tree leg 38 will be moved to a shoe shaping position where its shoe form 74 will be located between the presser pads 128 and 130. The appropriate treadle 142 will now be depressed to move the pads against the sides of the shoe on the shoe form with a wiping action which presses them against the sides of the shoe and rolls the top portion of the upper over the top of the lining, and will be latched in this position so as

to hold the pads in pressing engagement with the shoe upper while a shoe which has been shaped on the other shoe form is being brushed, removed from the form and another shoe is placed upon the form and the appropriate treeing operations are carried out. Pressure from the pads will cause the shoe to take the shape of the shoe form which will result in reducing the width of the shoe opening and giving it a symmetrical appearance. The heat from the shoe forms will accelerate the drying of shoes which have been dampened in the preceding cleaning operation and the concentration of the heat in the area adjacent the shoe opening will have a shrinking effect on the area of the upper around the top line of the shoe which will tend to reduce the shoe opening and will assist the pads 128, 130 in shaping the shoe opening. After the shoe treeing operations are completed on the shoe mounted on the tree leg 38, the presser pads 128, 138 will be released from engagement with the shoe on the tree leg 36, which is now dried out somewhat in addition to being shaped, and that leg will be swung back into the treeing position where the shoe will be brushed and removed from the shoe form. When either of the shoe trees is out of the central position, the shoe form is held in its expanded position by the engagement of the roller 52 with the flange 18 which prevents the forward movement of the roller 52 and its sleeve 50 that would permit a like movement of the rod 46 and the accompanying contraction of the shoe form.

While the turret is pivoted in the machine chosen to illustrate this invention, the use of the shoe shaping means disclosed herein is not limited to a machine of this type but it is contemplated that it may be used in conjunction with other forms of shoe tree mountings, such as those which are slidable or movable otherwise. All that is necessary in any event is that the shoe form be available to the shoe shaping means either before or after the treeing operations, preferably after.

Having thus described our invention, what we claim as new and desire to secure by Letters Patent of the United States is:

1. In a shoe treeing and shaping machine, a movably mounted support, spaced shoe forms mounted on the support for movement relatively thereto and also for movement with the support into and out of a treeing position, and shoe pressing means disposed in the path of movement of the shoe forms and arranged for pressing engagement with a shoe form which is out of treeing position.

2. In a shoe treeing and shaping machine, spaced shoe forms, spaced pressing means differently spaced than the shoe forms and arranged for engagement with said shoe forms, the shoe forms and the presser means being arranged for relative movement whereby one of said forms is available for treeing operations when the other form is in pressing engagement with the shoe pressing means.

3. In a shoe upper treeing and shaping machine, a pair of spaced shoe pressing means, a pair of movably mounted spaced shoe forms arranged for movement into and out of engagement with said shoe pressing means, the spacing of said shoe forms being different from that of the shoe pressing means whereby one of the shoe forms is always available for treeing operations while the other form is in pressing engagement with the shoe pressing means.

4. In a shoe upper treeing and shaping ma-

chine having a treeing position, a pair of spaced shoe forms pivoted to swing laterally, shoe pressing means located in the path of movement of said shoe forms on opposite sides of the treeing position, said shoe pressing means being spaced a different distance than the spacing of the shoe forms whereby one of the shoe forms is always available for treeing operations when the other form is in pressing engagement with its adjacent shoe pressing means.

5. In a shoe upper treeing and shaping machine, a movable support having spaced shoe forms mounted thereon, said support being arranged to move the shoe forms into and out of a treeing position, shoe pressing means on opposite sides of the treeing position and arranged in the path of movement of the shoe forms, each of said pressing means comprising a pair of normally spaced pressing members arranged to receive a shoe form between them, and means for forcing the presser members against the uppers of a shoe on that form which is out of treeing position to cause it to take the shape of the shoe form.

6. In a shoe upper treeing and shaping machine having a treeing position, shoe pressing means on opposite sides of the treeing position, a support mounted to move between said pressing means, a pair of spaced heated shoe forms mounted on the support for movement into and out of the shoe treeing position, the spacing of the shoe forms being such that when one of the shoe forms is in the treeing position the other shoe form is disposed for pressing engagement with one of the shoe pressing means whereby a shoe which has just been treed may be dried and shaped while treeing operations are being concomitantly carried out on a shoe on the other shoe form.

7. In a shoe upper treeing and shaping machine, a shoe form mounted for movement between a treeing position and a shaping position, said shoe form also being mounted for movement while in the treeing position to facilitate the treeing operation, and shoe pressing means arranged for pressing engagement with a shoe on the shoe form when the shoe form is in the shaping position.

8. In a shoe upper treeing and shaping machine having spaced treeing and shaping positions, a shoe form mounted for movement between the treeing position and the shaping position, and shoe pressing means mounted on the machine in the shaping position and arranged for movement into engagement with the upper of a shoe on the shoe form adjacent the foot receiving opening thereof when the shoe form is in the shaping position whereby a shoe which has been treed may simultaneously be dried and shaped.

9. In a shoe upper treeing and shaping machine, a movable support having a shoe form mounted thereon, said support being arranged to move the shoe form into and out of a treeing position, shoe pressing means offset from the treeing position and arranged in the path of movement of the shoe form, said pressing means comprising a pair of spaced pivoted presser members arranged to receive the shoe form between them, and means for rotating the presser members to bring them into wiping engagement with the sides of a shoe on the shoe form thereby to press the upper against the form and roll the top edge of the shoe upper over the top of the lining.

10. In a shoe treeing and shaping machine, a

shoe form mounted for movement into and out of a treeing position, shoe pressing means spaced from the treeing position, said shoe pressing means being disposed in the path of movement

5 of the shoe form and arranged for pressing engagement with the shoe form when it is out of treeing position, and means for heating said shoe form thereby to assist in drying and shaping shoes which have been dampened in the treeing

10 operations.

11. In a shoe upper treating machine having spaced treeing and upper shaping positions, a shoe form, a pivoted support for said shoe form arranged to move the form between the treeing 15 and the upper shaping positions, said shoe form being adjustably mounted on the support so that its position can be changed while in the treeing position to present different surfaces of a shoe upper for treeing operations, and shoe pressing 20 means arranged for engagement with a shoe on the shoe form when the form is in the upper shaping position.

12. In a shoe upper treating machine having spaced treeing and upper shaping positions, a shoe form, a pivoted support for said shoe form arranged to move the form between the treeing and the upper shaping positions, said shoe form being mounted on the support to rotate about an axis extending at an angle to the axis of rotation of the support whereby the support can be adjusted while in the treeing position to present different surfaces of the upper of a shoe on the form for treeing operations, and shoe pressing means arranged for engagement with the shoe upper when the form is in the upper shaping position.

13. In a shoe treeing machine, a rotatable support having a shoe form mounted thereon for movement into and out of the treeing position, 40 electrical heating means for the shoe form, said form being mounted on the support to rotate about an axis extending at an angle to the axis of rotation of the support, and connections including terminal means on the support for transmitting electricity to the heating means in all of the positions of adjustment of the shoe form.

14. A machine as defined in claim 13 wherein shoe pressing means are disposed in the path of movement of the shoe form and are arranged 45 for pressing engagement with the shoe form when it is out of treeing position.

15. In a shoe treeing and shaping machine having shoe pressing means, a tree leg mounted for movement between a treeing position and a shaping position where it is adapted to be engaged by the shoe pressing means, said tree leg embodying an expandable shoe form which comprises a heel part that is fixed relatively to the tree leg and an adjustable forepart, and mechanism for causing relative movement between the heel part and forepart.

16. In a shoe shaping machine having shoe pressing means, an expandable shoe form comprising a heel portion of heat conducting material, 65 and a forepart mounted for movement relatively to the heel portion, plates of heat conducting material arranged to engage the inner sides of a shoe on the form, said side plates being disposed in heat conducting relation to the heel portion, and means for heating the heat conducting portions of the shoe form thereby to apply heat to the sides and heel portion of a shoe on the form to facilitate the shoe shaping operations by elimi-

nating wrinkles in the upper and causing the upper to conform more readily to the shoe form when the shoe pressing means is applied to a shoe on the shoe form.

17. In a shoe shaping machine an expandable 5 shoe form comprising a heel portion of heat conducting material, a forepart slidably mounted on the body of the shoe form, side plates also of heat conducting material coupled to the forepart and arranged to engage the inner sides of a shoe 10 on the form adjacent the top opening thereof, bridging means of heat conducting material on the shoe form for bridging the gap formed between the side pieces and the heel portion upon relative movement between those members, and 15 means for heating the sides, bridging means and heel portion of the shoe form adjacent to the top opening of a shoe on the shoe form thereby to facilitate the shoe shaping operation.

18. In a shoe treeing and shaping machine having shoe pressing means, a shoe form mounted for movement between a treeing position and a shaping position where it is adapted to be engaged by the shoe pressing means, said shoe form having inwardly sloping sides in the area adjacent the foot-receiving opening of a shoe placed thereon, and means for causing pressing engagement between the shoe pressing means and the shoe form thereby to force the shoe upper against the inwardly sloping sides of the form to reduce the width of the shoe opening.

19. A machine for shaping shoe uppers comprising a pair of presser members, a heated shoe form having a narrow heel portion and inwardly sloping sides which diverge from the heel portion 35 to the throat portion, said shoe form being mounted for movement into a position between the presser members, and means for forcing the presser members against the upper of a shoe on the form to press the same against the inwardly 40 sloping sides of the heated form to reduce the shoe opening.

20. A machine as defined in claim 18 wherein the shoe form is expandable and the heel portion thereof is relatively narrow and has a rear portion which slopes abruptly downwardly and forwardly of a shoe thereon whereby, upon the completion of a pressing operation, the form may be collapsed and removed from a shoe without dis- 45 turning its shape.

21. In a machine for shaping shoe uppers having shoe pressing means, a heated shoe form comprising a heel portion and a forepart slidably mounted on the heel part, said heel portion having inwardly and upwardly sloping sides of heat 55 conducting material disposed for engagement with the top portion of the upper of a shoe placed thereon, the sloping sides of the heel section extending part way to the throat portion of the shoe form, side plates coupled with the forepart 60 and slidably mounted on said heel portion, the side plates having inwardly sloping sides of heat conducting material also disposed for engagement with the top portion of the upper of a shoe on the form, said side plates extending from the 65 throat section back toward the heel portion, and means for heating the inwardly sloping side portions of the shoe form thereby to facilitate the shoe shaping operations in the top portion of the upper of a shoe pressed thereagainst by the 70 shoe pressing means.
